JOHN J. CRAWFORD, OF NEW YORK, N. Y.

VEHICLE-SPRING SHACKLE.

1,185,378.

Specification of Letters Patent. Patented May 30, 1916.

Application filed August 12, 1915. Serial No. 45,143.

To all whom it may concern:

Be it known that I, JOHN J. CRAWFORD, a citizen of the United States, and a resident of the city of New York, West New 5 Brighton, borough of Richmond, in the county of Richmond and State of New York, have invented a new and Improved Vehicle-Spring Shackle, of which the following is a full, clear, and exact description.

Among the principal objects which the present invention has in view are: to provide a relatively sensitive resilient connection for the ends of leaf springs for absorbing the minor vibrations and for preventing 10 the snapping of the top leaf incident to the lift of a vehicle body; to provide a shackle of the character mentioned formed as a single unit, simple in design and easily applied; to provide a shackle of the character mentioned shaped to replace the conventional link shackle, thereby avoiding the necessity 15 for special parts or alterations in the construction of conventional parts.

Drawings.—Figure 1 is a side view of a 20 fragment of an automobile chassis, a fragment of a carrying spring therefor, and a shackle connecting the same constructed and arranged in accordance with the present invention; and Fig. 2 is a top view of the 25 shackle so constructed.

Description.—As seen in the drawings, a bracket 7 is rigidly mounted upon a side bar 8 of an automobile chassis. The bracket and chassis disclosed are of conventional form 30 and manufacture. The top leaf of spring 9 is constructed to receive the shackle bolt 10. A similar bolt 11 is mounted in bearings formed in the bracket 7. Conventionally, the bolts 10 and 11 form pivot connecting 35 members for rigid shackle link. In accordance with the present invention, these bolts perform the same office for the bowed spring shackle 12.

The shackle 12 is constructed from finely 40 tempered spring steel. The size and cross section of the body of the spring is designed according to the installation and in accord-

ance with the calculated weight to be suspended on the springs, such as 9. The ends of the shackle 12 are yoked to form hinge 50 knuckles 13. The knuckles 13 are suitably perforated to receive the bolts 10 and 11 and to straddle the ends of the top leaf of the spring 9 and the lower end of the bracket 7.

In each installation, the load compression 55 of the shackle 12 is estimated and provided for. The bending moment of the shackle 12 is designed to a lower stress than the spring 9. Consequently the vibration of the spring 9 occasioned by the road is absorbed by the 60 shackle 12. Also when the wheel is suddenly elevated by the road, the spring 9 compresses the shackle 12 to a point where the bending stress of the said shackle equals the bending stress of the spring 9, before 65 the spring 9 is deflected. In this manner the carrying spring 9 is relieved of a large portion of the road shock. When, on the other hand, the axle and chassis are forced apart beyond the normal, where conventionally 70 the upper leaf of the spring 9 would be deflected upward, the shackle 12 yields before the upper leaf and absorbs the "whip" or "back lash" of the spring and parts connected therewith. In this way the cause of 75 breakage common to springs characterized as above, is removed.

Claim:

As an article of manufacture, a vehicle 80 spring shackle comprising a relatively narrow, bowed, resilient body having integrally formed laterally extended hinge members, said knuckles being spaced apart for overlapping the side edges of the vehicle elements with which said shackle is operatively 85 connected.

In witness whereof I have signed my name to this specification in the presence of two subscribing witnesses.

JOHN J. CRAWFORD.
